UNITED STATES PATENT OFFICE

HENRY P. KIRCHNER, OF NIAGARA FALLS, NEW YORK, ASSIGNOR TO THE CARBORUNDUM COMPANY, OF NIAGARA FALLS, NEW YORK, A CORPORATION OF PENNSYLVANIA

FURNACE AND METHOD OF OPERATING THE SAME

Application filed July 21, 1930. Serial No. 469,494.

This invention relates to furnaces and to the method of operating the same, and relates more particularly to the protection of the refractories under extremely severe temperature and slagging conditions. The invention has special application to the burning of powdered coal as a fuel in boiler furnaces because of the severity of the conditions imposed upon the refractory forming 5 the combustion chamber, but it is not limited to such installations.

In the operation of boilers using powdered coal as a fuel, it is the practice to run the boilers at several hundred percent of their 10 ordinary or normal rating. The limit at which the boilers may be run is determined to a very large extent on the ability of the refractory to stand up for any appreciable length of time at the high temperatures employed and under the destructive action of 15 the slag. The rate of combustion in restricted portions of the combustion chamber may reach 100,000 B. t. u.'s per cubic foot per hour. This means temperatures of the order of 20 magnitude of 2700 degrees F. in such combustion regions. The heating of the walls of the combustion chamber is correspondingly severe. In such cases fire-clay walls which are subjected to the fluxing action of the slag 25 30 in the neighborhood of such intense combustion are rapidly disintegrated.

Fire-clay is a relatively poor conductor of heat. Consequently, there is no way in which the high temperature existing at the 35 exposed face of the wall can be reduced by the dissipation of heat through the wall itself. A fire-clay wall of sufficient thickness to have mechanical stability at high temperatures is too good an insulator to permit 40 of the use of any system of cooling on the outside of the wall. There is, therefore, no way in which the wall can be protected from slag erosion and the furnace must either be operated at a relatively lower temperature, 45 or it must be operated without regard to the maintenance of the refractory.

To remedy this it has been proposed to use silicon carbide as a refractory for this type of furnace. Silicon carbide is three times as 50 strong as fire-clay at these high tempera-

tures and is from six to nine times more thermally conductive. This means that a wall having the same mechanical stability can be about one-third the thickness of a corresponding fire-clay wall. If the material is nine times more thermally conductive than fire-clay, heat may be dissipated through the wall twenty-seven times faster than it can through a fire-clay wall of equal mechanical stability at operating temperatures. The heat conducted through the walls is carried away by a current of air circulated against the unexposed face of the wall. Due to the high conductivity of the silicon carbide refractory wall the rate of cooling can be made directly responsive to the change in the velocity of the air circulating against the wall. The air so used can be returned to the combustion chamber to support combustion in the furnace, thus increasing the rate of combustion and preventing a needless waste of heat. By circulating a sufficient volume of cold air against the unexposed face of the silicon carbide wall it is possible to cool the exposed face of the refractory to a point where the slag immediately in contact with the face of the wall congeals, forming a thin protecting skin or film of slag over the face of the refractory. 55 60 65 70 75

This not only protects the refractory against the erosive action of the slag, but also prevents any oxidation of the carbon in the silicon carbide or any reaction between the silicon carbide and the slag. 80

Congealed slag has a lower thermal conductivity than silicon carbide. It has been further possible, by reason of the arrangement above described, to obtain a condition in which silicon carbide bricks can be cooled sufficiently by internal cooling of the wall to keep the exposed face of the wall covered with a layer of congealed slag about one-quarter of an inch thick. A temperature gradient is established through the furnace wall in which the rate of fall of temperature is more rapid in passing through the congealed slag film than in passing through the silicon carbide itself. This method of operation is described and claimed in a copending application of C. E. Hawke, Serial No. 244,784, filed January 5, 1928. This application 85 90 95 100

cation has become U. S. Patent #1,833,677. This method of operation is subject, however, to certain limitations. One of these is that the cooling action of the air diminishes with the increase in the temperature of the air. In circulating past the unexposed face of the highly heated silicon carbide walls, the temperature of the air is rapidly raised. This means that as it continues to flow through the circulating passage provided back of the silicon carbide wall, its cooling effect continuously diminishes. This can be remedied, of course, by using an increased volume of air, but if this be done, more air is employed than can be efficiently used in the combustion chamber. This disadvantage has been partly overcome by placing water tubes in the air passage so that the air which wipes the silicon carbide wall and absorbs heat therefrom wipes against the water pipes and imparts heat thereto. The air is thus cooled to a considerable extent. This is disclosed in a copending application of R. C. Benner, Serial No. 239,724, filed December 13, 1927. This application has become U. S. Patent #1,786,593.

However, in the operation of furnaces, and particularly powdered coal furnaces, there is a considerable change in the temperature of the walls when the output of the boiler is changed. Changes of boiler rating are the main cause (but not necessarily the only cause) of changes of wall temperature. These changes result in the production of areas over the furnace wall which are substantially hotter than other areas. Inasmuch as the maintenance of the silicon carbide at these high temperatures in an intensely oxidizing atmosphere and in the presence of highly reactive slags is dependent upon the maintenance of the congealed coating of slag, it is evident that (as a consequence of the production of a hot area where the slag does not congeal or where the temperature of the exposed face rises above the congealing point) the refractory will lose its protection and be exposed to destruction.

According to the present invention I provide a method of correcting this condition by selectively cooling different portions of the wall to a greater extent than other portions according to the requirements of a particular area. I provide a furnace wherein the temperatures of different areas may be determined, and provide a furnace wherein different individual areas are susceptible of selective cooling to a greater or lesser extent.

The invention may be readily understood by reference to the accompanying drawings in which:

Figure 1 is a more or less diagrammatic view of a steam boiler installation having a powdered coal burner, the view representing a vertical section through the installation;

Figure 2 is a more or less diagrammatic

view showing a fragmentary horizontal section of a portion of a wall of the combustion chamber;

Figure 3 is a diagrammatic view of a meter board of the type which may be conveniently used in the system;

Figure 4 is a front view of the signal board with which the meter board cooperates; and

Figure 5 shows a type of automatic regulator which may be employed with the method.

Referring to the drawings, a pulverizing fan 2 feeds coal from a hopper 3 through a feeder pipe 4 into the combustion space of a furnace, designated generally as 5. The boilers are outlined at 6. The interior of the combustion chamber 5 is lined with a refractory material having a coefficient of thermal conductivity which is relatively high as compared with fire-clay, and which is in excess of $0.006 \text{ cal/cm}^2/\text{sec}^{\circ}\text{C}$. The lining, designated generally as 8, may be made, for example, of bonded silicon carbide. The thermal conductivity of this material is from six to nine times that of fire-clay. Surrounding the inner wall 8 and in spaced relation thereto is an outer wall 9, the shell 9 preferably being of fire-clay or other insulating refractory. Between the walls 8 and 9 is an air circulating passage 7. Air is supplied to the space 7 by a fan 11 which forces air through a pipe 12 into the space 7 through a port 13. The air which is forced or circulated through the space 7 is discharged through a pipe 14 which communicates with a chamber 15 surrounding the turbulent burner 16. The pipe 4 terminates at the turbulent burner 16. The arrangement is such that air which is forced through the space 7 between the silicon carbide wall 8 and the outer shell of the furnace is discharged with the fuel into the combustion chamber. The primary air enters along with the coal through the feeder pipe 4, and the secondary air comes in through chamber 15. A push rod 17 is used for varying the position of the baffle or reflector 16' in such a way that the shape of the flame can be altered.

At various points about the wall 8 and in different parts of the combustion chamber are thermocouples so arranged that the junctions lie in the conducting refractory close to the exposed surface thereof. These thermocouples, which are diagrammatically illustrated, are designated 20. As shown in Fig. 2, separate lead wires go from the thermocouples to conveniently located indicators. These may comprise a series of meters, as shown in Fig. 3. These meters, which constitute a form of D'Arsonval galvanometer, are indicated as having a suspended armature A carrying a mirror M located between poles S and N of a permanent magnet. As well understood by those skilled in the art, this type of meter is very sensitive to small

temperature changes. A separate meter is provided for each thermocouple in the furnace wall.

Cooperating with the meter board of Fig. 3 is a signal board, as shown in Fig. 4, the signal board being designated generally as 21. It is provided with a plurality of windows 22, each of which is divided into three areas of differently colored glass. The first marked W is clear, the next marked Y is yellow, and the third marked R is red. Beams of light reflected from the mirrors M of the several meters fall on the correspondingly positioned windows. The beam of light under normal operating conditions falls on the sections W of the respective windows, but as the furnace wall for a given thermocouple becomes more highly heated than desired, the mirror M of the galvanometer connected to the thermocouple in that particular section rotates, reflecting the beam first onto the Y area and then onto the R area.

By reason of this arrangement the operator is enabled to know the approximate temperature conditions under which each small area of the wall is operating. He can tell when any section of the wall is becoming dangerously overheated.

Located in the furnace wall adjacent each thermocouple is an air inlet passage 23. This air inlet passage, opening into the space 7 adjacent each thermocouple, is connected to a source of air supply, which may be the blower 11, or as shown in Figs. 1 and 2, it may be an auxiliary blower 24. For this purpose I have shown a conduit 25 leading from the blower 24 with branches extending to each of the connections 23. Each connection 23 is provided with its own individual valve 26. When a thermocouple indicates to the operator that a given portion of the wall is getting too hot, the valve 26 in the air passage 23 most nearly located to that particular thermocouple is opened, allowing fresh cold air to enter that portion of the circulating passage 7 and cool the portion of the wall being overheated. The valve 23 is then adjusted to a position which will maintain the desired temperature balance which keeps continuously a protecting coating of slag on that particular part of the wall.

In the particular embodiment shown in Figs. 1 and 2 I have shown the fan 11 with an adjustable damper 52 as constituting a means for forcing a normal current of air through the passage 7. The fan 24 with its outlet duct 25 and distributing passages 23 connected therewith constitute more or less auxiliary air supply means. In each of the passages 23 is an adjusting valve 26. It will be understood, however, that it is not necessary to provide the fan 11, since all of the air for cooling may be supplied by the fan 24 which can be used to maintain the desired draft through the space 7, the distribution of the

entering air being changed from time to time by adjusting the valves 26 as may be necessary on account of change of boiler output and consequent change of temperature distribution in the furnace.

In the drawings I have shown water pipes 27 in the air circulating space 7. These are connected at the top thereof to a common header 28, and at the bottom to a common header 29. By means of valves 30 and 31 the flow of water or other cooling fluid through the pipes 27 may be controlled and the direction of flow determined. The air in the passage 7, circulating against these pipes, transfers heat to the water or other cooling fluid contained therein, and thus serves to cool the air. The water circulation therefore diminishes the amount of air required in the cooling of the furnace to a point where a greater proportion of the air used for cooling can also be used for combustion. This results in a more economical operation of the furnace.

In practicing the invention it is of course understood that a boiler furnace using powdered coal fuel is under the operation of a skilled operator. The operator, according to the signals indicated on the signal board 21, selectively varies the distribution and circulation of air to and back of any particular wall section in accordance with the requirements of that section. In this way overheating of any portion of the wall can be varied, and as the hotter areas shift about due to the changes in the boiler output (and consequently boiler rating) the operator may selectively vary the degree of cooling obtained at any one point. This enables all sections of the wall to be operated at the temperature desired and without overheating in any particular portion of the furnace. General conditions can be taken care of by varying the amount of air supplied by the fan 11 and through controlled circulation of fluid in the pipes or conduits 27. Localized conditions are taken care of by means of the auxiliary ducts 23 and their control valves 26.

Through an arrangement of this kind it is possible to maintain a congealed coating of slag of the necessary thickness over different individual portions of the entire area notwithstanding the fact that some portions are heated more intensely than others and notwithstanding the fact that there may be a shifting of the more intensely heated portions from one area to another. By the use of the precautions I have described even the hottest portion of the furnace wall may be kept below the melting point of the fuel ash under proper operating conditions of the burner.

If desired, automatic operation of the individual valves 26 may be employed. One type of apparatus for doing this is disclosed in Fig. 5 wherein the valve, corresponding to the valve 26, is designated 42, while the pipe corresponding to the conduit 23 is desig-

nated 43. A thermocouple 40 is located in the wall 8 as previously described, and the leads from this thermocouple are connected to a relay 41. The relay 41 is a temperature control unit such as is well known in the art and such as is used for reversing motors employed to adjust valves in ventilating systems or water supply systems. The relay 5 functions to connect the lines L—L or the lines H—H with current supply lines S—S. The lines L—L and H—H lead to a motor 44. The motor 44 drives an eccentric 46 through a speed reducer 45. The eccentric 46 operates a bell crank lever 47. The lever 47 10 is connected through a link 48 with a valve operating extension 49. Upon rocking the lever 47 in one direction the valve 42 is opened and upon moving it in the other direction the valve is closed. When the motor is energized 15 through the lines L—L the motor operates in a direction to close the valve 42 and when the motor is energized through the lines H—H it is operated to open the valve and permit fresh air to enter the section of 20 wall in which the thermocouple 40 is located. 25 At 51 is a snap-action limit switch which operates after a predetermined movement of the lever 47 to prevent the motor from operating to open the valve or close the valve more than a predetermined extent. Connected in 30 the line S—S is an interrupter 50 the purpose of which is to close the circuit to the relay 41 at predetermined time intervals only. It is not desirable that the motor should 35 operate too frequently, and the interrupter 50 permits its operation only at predetermined time intervals. When the interrupter is open the motor cannot run and a certain equilibrium in the portion of the wall being 40 controlled is effected. During this time that the motor cannot operate a definite temperature gradient in the silicon carbide lining and slag coating may be reached and a continuous fluctuating of the valve first one way and 45 then the other is avoided. If the temperature at the thermal junction is too hot or too cold for the formation of a coating of slag of the desired thickness, this condition is altered during the next closed period of the inter- 50 rupter.

I have not shown the wiring in detail, as it embodies merely the use of well-known electrical mechanism, and the details of the motor control circuit are known to those 55 skilled in the art.

While I have shown and described certain specific embodiments of my invention, it will be understood that this is merely by way of illustration and that various changes and 60 modifications in the details of construction and arrangement of parts may be made within the contemplation of my invention and under the scope of the following claims.

I claim:

65 1. In the method of operating a furnace

having an air cooled silicon carbide wall, the steps which comprise circulating a current of air back of the exposed face of the wall, cooling the air whereby the volume of air required is reduced, and selectively applying 70 additional air to different portions of the wall where the temperature conditions are more severe.

2. In a powdered coal furnace means for selectively controlling the surface temperatures of the combustion chamber comprising an inner lining of refractory having a thermal conductivity greater than

75 .006 cal/cm²/sec/°C.,

80 an outer lining of insulating refractory spaced from said inner lining to form a space for cooling air in motion, means for supplying the main body of such air at a sufficient rate to regulate the temperature of the major portion of the furnace wall, and additional means for supplying cooling air to regulate the temperatures of selected regions of the inner wall.

85 3. In a powdered coal furnace an inner wall consisting substantially of silicon carbide, an outer lining of insulating refractory spaced from said inner lining to form a space for cooling air in motion, means for supplying the main body of such air at a sufficient rate to regulate the temperature of the major portion of the furnace wall, and additional means for supplying more cooling air to hotter individual areas of the inner lining, said additional means being automatically controlled in accordance with the 90 temperatures of such individual areas.

95 In testimony whereof I have hereunto set my hand.

HENRY P. KIRCHNER.
